UNITED STATES PATENT OFFICE.

JOHN ROBINSON, OF DETROIT, MICHIGAN.

DOPE-CUP.

SPECIFICATION forming part of Letters Patent No. 433,149, dated July 29, 1890.

Application filed April 1, 1890. Serial No. 346,240. (No model.)

To all whom it may concern:

Be it known that I, JOHN ROBINSON, a citizen of the United States, residing at Detroit, in the county of Wayne and State of Michigan, have invented certain new and useful Improvements in Dope-Cups, of which the following is a specification, reference being had therein to the accompanying drawings.

This invention relates to new and useful improvements in dope-cups; and the invention consists in the peculiar construction of mechanism for making a constant force-feed of the dope to a crank-pin or other point desired to be oiled, the motion of the feed mechanism being imparted from the movement of the machinery, and, further, in the peculiar construction, arrangement, and combination of the various parts, all as more fully herein-after described.

I have shown my cup as applied to a crank-pin in the accompanying drawings, in which—

Figure 1 is a side elevation of my device as in use. Fig. 2 is an enlarged elevation of the cup, with the casing in vertical central section. Fig. 3 is a horizontal section on line xx ; Fig. 2. Fig. 4 is a horizontal section of the stem on line yy , Fig. 2.

A is the casing, having a suitable hollow shank B exteriorly threaded to be secured upon the crank-shaft above the pin, and having a suitable cap C detachably secured by means of the set-screws C'.

D is a screw-threaded stem secured centrally within the casing, and having secured to its lower end the piston-head D', fitting closely the inside of the casing. The stem D is provided with a keyway a its entire length, in which engages a feather upon the collar E, the upper one of which is secured to the top

40 of the cap and the lower one to the partition F.

G is an annular pinion interiorly screw-threaded to receive the screw-threaded stem D, and secured between the collars E. Motion is imparted to this pinion from the worm-

45 gear c, formed upon the collar d, which is loosely sleeved upon the shaft II, extending through the cap upon one side, its outer end being provided with a ratchet-wheel I and the bell-crank lever I', the arm e of which carries

50 the spring-pawl f, engaging with the ratchet-wheel I, the arm g of which is pivotally con-

nected to the connecting-rod h, which, at its lower end, connects to the pin i, which is secured upon the adjustable plate j, which is secured to the crank-pin k by means of the 55 set-screw l, engaging in a slotted bearing l', all so arranged that the movement of the crank with its pin carrying the plate j and the pin i, which is eccentrically arranged in relation to the crank-pin, will rock the bell- 60 crank lever I'.

The rocking movement of the bell-crank lever upon its pivot will turn the ratchet-wheel I one or more notches through the medium of the pawl f, thus causing the rotation of 65 the shaft II and the sleeve d, having the worm-gear c meshing with the pinion G, causing it to rotate, and by means of its interior screw-thread will lower the stem D, which is prevented from rotating by means of the feather 70 upon the collar E engaging in the keyway a, thus gradually forcing down the piston-head D' and feeding the dope through the aperture in the shank B to the pin to be oiled.

To cause the collar d to turn with the shaft 75 II, I form a squared portion m upon the shaft II, upon which is slidably secured the clutch n, having pins o engaging suitable apertures in the collar d, and held in such position by means of the spring p bearing against the lever q, which is pivoted at q'. This lever has the forward-projecting arm r, having the head r', which is provided on its inner surface with an inclined face r''. A pin s upon the lever r engages in the groove s' in the clutch. 80

85 t is a pinion secured upon the collar d, meshing with the bevel gear-wheel t' upon the shaft t'', which projects through the casing, and to which is secured a suitable crank-handle u.

90 The parts being thus constructed, their operation is as follows: The stem is raised to its highest position by turning upon the crank u, which imparts motion through the gear-wheel t' and pinion t to the collar d, reversing the 95 motion of the stem D and lifting the piston-head D' to its highest position. The cup may be now filled with dope and the cap secured in position. The motion of the crank will operate as above described and depress the 100 piston-head D' to feed the dope to the pin. When the pin has reached the bottom of its

movement, in order that the parts may not be damaged by its further progress, the head D^2 of the stem will strike upon the inclined face r'' , throw the lever q against the action 5 of the spring p , and disengage the pins o from the apertures in the collar d . The further motion of the machinery will simply rotate the shaft H loosely within the collar d without imparting motion to the same.

10 In order to make the cup feed more or less rapidly, I adjust the adjustable plate j in or out from the center of the crank-pin, thereby giving more or less movement to the bell-crank lever and to the operating mechanism.

15 What I claim as my invention is—

1. In an oil-cup, a vertically-moving piston, means for forcing the same down, and a trip engaging with the piston when it is at its lowest point for disengaging the operating means, 20 substantially as described.

2. In an oil-cup, a vertically-movable piston, a worm-gear engaging the same for forcing it down, means for actuating the gear, and a trip operated by the piston to disengage the gear from its operating means, substantially as described.

3. In a dope-cup, the combination of the casing, the screw-threaded piston-stem, the shaft H , and connecting-gearing, connection 25 between an eccentric-pin i upon the crank-pin, and the shaft H for imparting motion thereto, the collar d upon said shaft, the clutch

n , having pins o , engaging with said collar, the spring p , lever q , arm r , head r' , incline r'' , adapted to be struck by the head D^2 of 35 the stem, substantially as described.

4. In an oil-cup, the combination, with the screw-threaded stem of a piston, of a worm-gear for operating the same, a shaft on which said gear is loosely mounted, a clutch, and a trip 40 for actuating the clutch when the piston is at its lowermost point, substantially as described.

5. In an oil-cup, the combination, with the screw-threaded stem of a piston, of a gear-wheel surrounding the same having a threaded 45 center, a worm-gear meshing with the gear, means for actuating the worm, and a clutch operated by the movement of the stem for disengaging the worm-actuating means from the worm, substantially as described. 50

6. In an oil-cup, the combination of the stem of a piston and means for forcing the same down, of an inclined trip for engaging with the stem while on its downward movement, and a clutch operated by said trip, substantially as described.

In testimony whereof I affix my signature, in presence of two witnesses, this 26th day of February, 1890.

JOHN ROBINSON.
